Atty.

UNITED STATES PATENT OFFICE.

JOHN L. McKEOWN, OF CHICAGO, ILLINOIS.

TRUSS.

Application filed December 8, 1920. Serial No. 429,188.

To all whom it may concern:

Be it known that I, JOHN LATTIMER McKEOWN, a citizen of the United States, and resident of Chicago, in the county of Cook 5 and State of Illinois, have invented a new and useful Truss, of which the following is a specification.

This invention relates to trusses and relates particularly to lattice trusses.

10 The object of the invention is to provide a truss particularly designed and especially adapted for supporting the roofs of grandstands, amphitheatres and similar structures, which, in addition to the roof proper, 15 comprise a projecting portion or canopy adapted to protect the occupants of the structure from the sun and weather.

A further object of the invention is to provide a truss for the purpose specified, 20 of such construction that the projecting portion of the roof will not obstruct the view from said grandstand or other structure.

To effect the foregoing objects, my improved truss comprises a main section and what may be described as a cantilever section. As shown, said main section consists of a usual form of lattice truss comprising a bowed top chord, a substantially straight 30 bottom chord, means connecting said chords at their ends, and lattice members which connect said top and bottom chords; and said cantilever section comprises an arm bowed reversely to the curvature of the top 35 chord of the main section of the truss and which preferably forms a continuation thereof, a top chord or member which connects the outer end of said cantilever arm with the bowed top chord of the main section of the truss intermediate its ends, the top edge of said chord being preferably substantially continuous with the upper edge of the top chord of the main section of the truss at its highest point, whereby the top 40 edges of said chords will be continuous with each other, and lattice members which connect the top chord of said cantilever section with the cantilever arm thereof and also with the top and bottom chords of 45 the main truss section, said lattice members, so far as possible, forming extensions of the lattice members connecting the top and bottom chords of the main section of the truss. The invention also comprises the various 50

other features and details of construction 55 hereinafter described and claimed.

In the accompanying drawings, in which my invention is fully illustrated—

Figure 1 is a side view of a truss of my invention, shown as applied in use for supporting the roof of a grand-stand or the like.

Figure 2 is an enlarged fragmentary, detail view showing means for connecting the front ends of the top and bottom chords of 65 the main section of the truss to each other and also to the post or column which supports the front end of the main section of said truss.

Figure 3 is an enlarged fragmentary sectional view on the line 3—3 of Fig. 2; and

Figure 4 is an enlarged view on the line 4—4 of Fig. 1.

Referring now to the drawings in which, for purposes of definite and concrete illustration, I have shown a truss of my invention as applied in use for supporting the roof of a grand-stand or similar structure, A designates my improved truss as a whole, B, B' posts or columns for supporting the 75 front and rear ends, respectively, of the roof structure and C the roof covering, comprising joists c and sheathing c'.

In accordance with my invention the truss A comprises a main section designated as a 80 whole A' and what may be described as a cantilever section A².

As shown, the main section A' of my improved truss consists of a usual form of lattice truss, comprising a bowed top chord 90 1, a bottom chord 2 and lattice members 3.

As shown, said top and bottom chords 1 and 2 are of a familiar type comprising separated sections between which the lattice members 3 are secured, the sections of 95 said top chord being formed by timbers bent flatwise and secured together to form a plurality of layers, the flat sides of said timbers being disposed substantially at right angle to lines normal to the curve 100 defined by said top chord. In like manner the bottom chord 2, as shown, consists of timbers secured together flatwise with their flat sides parallel with what may be referred to in a general way as the plane of 105 said truss.

As regards my present invention, however, the specific construction of the truss form-

ing the main section A of my improved truss is immaterial and I do not, therefore, desire to limit myself to the particular form of truss shown, or to any particular form 5 of truss.

The front ends of the top and bottom chords 1 and 2 of the main truss section A' are connected to each other and to the supporting post or column B by suitable means 10 consisting, as shown, of a strap 4 bent between its ends to extend over the top chord 1 with its end sections embracing the lateral sides of said top and bottom chords and of the post B, said strap being bolted or otherwise rigidly secured to said top and bottom 15 chords and to said post.

The cantilever section A² of the truss A comprises an arm 5 bowed reversely to the curvature of the top chord 1 of the main 20 truss section A', a chord 6 which connects the outer end of said cantilever arm with the top chord 1 of the main truss section A', and lattice members 7 which connect said cantilever arm 5 and chord 6 with each 25 other and also with the top and bottom chords of the main truss section A'.

As shown, the cantilever arm 5 and chord 6 comprises separated sections between which the lattice members 7 are secured, the 30 construction thereof, respectively, being the same as that of the top and bottom chords 1 and 2 of the main truss section A', the sections of said cantilever arm 5 preferably forming continuations or extensions of the 35 chord sections of said chord top 1.

Also, in order that the roof covering C may present an even surface, the chord 6 is preferably secured to the top chord 1 of the main truss section A' so that the upper 40 edges of said chords will be continuous with each other, convenient means for this purpose consisting of straps 8, said straps being bent between their ends to extend over the connected chords with their ends embracing and bolted or otherwise rigidly secured thereto.

In the particular application of my improved truss shown, the portion of the roof C, which projects in front of the supporting 50 posts B and is supported by the cantilever section A² of the trusses form the canopy of the roof.

I claim:

1. A truss comprising main and cantilever sections, the main section comprising top 55 and bottom chords, and lattice members which connect said chords, and the cantilever section comprising a cantilever arm, a chord which connects said cantilever arm with the top chord of the main truss section, 60 and lattice members which connect the chord of said cantilever section with the cantilever arm and also with the top chord of said main truss section, the relation being such that the cantilever section of the 65 truss will overlap the main section thereof, substantially as described.

2. A truss comprising main and cantilever sections substantially as specified in claim 1, in which the top chord of the main truss 70 section is bowed, substantially as described.

3. A truss comprising main and cantilever sections substantially as specified in claim 2, in which the cantilever arm is bowed reversely to the curvature of the top chord of 75 the main truss section, substantially as described.

4. A truss comprising main and cantilever sections substantially as specified in claim 1, in which the upper edge of the chord of 80 the cantilever section is continuous with the upper edge of the top chord of the main truss section, substantially as described.

5. A truss comprising main and cantilever sections substantially as specified in claim 1, in which the top chord of the main truss 85 section and the cantilever arm are continuous with each other, substantially as described.

6. A truss comprising main and cantilever sections as specified in claim 5, in which the top chord of the main truss section and the cantilever arm are reversibly bowed, substantially as described.

7. A truss comprising main and cantilever sections as specified in claim 1, in which lattice members of the over-lapping portions of the main and cantilever sections of 95 said truss are formed integral with each other, substantially as described.

In testimony that I claim the foregoing as my invention, I affix my signature this 22nd day of November, 1920.

JOHN L. McKEOWN.
